PRODUCE PACKAGE

Kenneth D. Bixler, Huntington, and Robert E. Ralphs, Katonah, N.Y., assignors to Diamond International Corporation, New York, N.Y., a corporation of Delaware

Filed Aug. 23, 1968, Ser. No. 13,246

Term of patent 14 years

Int. Cl. D9—05
U.S. Cl. D9—219

FIG. 1

FIG. 4

FIG. 2

FIG. 5

FIG. 3

FIG. 1 is a perspective view of a produce package showing the novel design;

FIG. 2 is a top plan view of FIG. 1;

FIG. 3 is a bottom plan view of FIG. 1;

FIG. 4 is a side elevational view of one side of the produce package of FIG. 1 (all sides having a similar appearance); and

FIG. 5 is a vertical section taken on line 5—5 of FIG. 2.

The characteristic feature of my design resides in the combination on the package disclosed of the particular lid, substantially as shown.

We claim:

The ornamental design for a produce package, as shown and described.
